UNITED STATES PATENT OFFICE

148,320

DESIGN FOR A HEARING AID CASE

William D. Penn, Dallas, Tex.

Application August 23, 1946, Serial No. 132,775

Term of patent 7 years

(Cl. D26—14)

To all whom it may concern:

Be it known that I, William D. Penn, a citizen of the United States, residing at Dallas in the county of Dallas and State of Texas, have invented a new, original, and ornamental Design for Hearing Aid Cases, of which the following is a specification, reference being had to the accompanying drawing, forming part thereof.

Fig. 1 is a side view of the hearing aid case showing my new design;

Fig. 2 is a front view; and

Fig. 3 is a back view.

I claim:

The ornamental design for a hearing aid case, as shown.

WILLIAM D. PENN.
